(74) Attorney, Agent, or Firm — Foley & Lardner LLP

(57) **CLAIM**

I claim the ornamental design for a nail trimmer, as shown and described.

DESCRIPTION

FIG. 1 is a front, left perspective view of an embodiment of the claimed design;

FIG. 2 is a front elevation view thereof;

FIG. 3 is a rear elevation view thereof;

FIG. 4 is a right elevation view thereof;

FIG. 5 is a left elevation view thereof;

FIG. 6 is a top plan view thereof; and,

FIG. 7 is a bottom plan view thereof.

The ornamental design which is claimed is shown in solid lines in the drawings.
